[57] CLAIM

The ornamental design for a wood pellet burning stove, as shown and described.

DESCRIPTION

FIG. 1 is a front elevational view of a wood pellet burning stove showing my new design;

FIG. 2 is a right side elevational view thereof;

FIG. 3 is a top plan view thereof;

FIG. 4 is a left side elevational view thereof;

FIG. 5 is a bottom view thereof; and

FIG. 6 is a rear elevational view thereof.

The side opposite the side illustrated in FIG. 2 is the same as illustrated in FIG. 2 except the hinges are not present, only a handle for use in opening the door.

FIG. 1.

FIG. 2.

FIG. 3.

FIG. 4.

FIG. 5.

FIG. 6.
